UNITED STATES PATENT OFFICE.

FREDERICK MAURICE LASERSON, OF NEW YORK, N. Y.

PORTRABLE SAW.

1,352,519.

Specification of Letters Patent. Patented Sept. 14, 1920.

Application filed December 30, 1918. Serial No. 268,790.

To all whom it may concern:

Be it known that I, FREDERICK MAURICE LASERSON, a subject of the King of England, residing at 100 Fifth avenue, city, 5 county, and State of New York, U. S. A., have invented new and useful Improvements in Portable Saws, of which the following is a specification.

This invention relates to portable saws. 10 The object of the invention is to provide a power driven saw so constructed and arranged that it may be operated where the ordinary saws cannot be used. A further object is to provide a base and support for 15 such a saw, and a mounting thereon for the saw blade and its operating means which will permit the saw blade to be moved with relation to its base or support. A more specific object is to provide means for indicating the depth of the cut of the saw and also means for limiting the depth of the cut. 20

The invention consists of the construction, combination and arrangement of parts, as herein illustrated, described and claimed.

25 In the accompanying drawings, forming part hereof, is illustrated a form of embodiment of the invention and one modification, in which drawings similar reference characters designate corresponding parts 30 and in which:

Figure 1 is a side elevation;

Fig. 2 is a plan view;

Fig. 3 is a horizontal section, taken approximately on line 3—3 of Fig. 1 looking 35 in the direction indicated by the arrows.

Referring to the drawings, 1 designates a standard to which are affixed feet 2. The feet 2 are pivoted on the standard 1 so that they may swing entirely around the standard, and are maintained thereon by means 40 of a cap 3 held in place by a screw 3a.

A bar 4 has one end secured to the standard 1 midway of its length and at its outer end is provided with a screw-threaded pin 5 45 on which is disposed an interiorly screw-threaded stop 6. One side of the screw-threaded pin 5 is flattened and has thereon a scale 7.

A loop 8 is formed on the outer end of 50 a handle 9 and is slidably disposed on the pin 5, so as to slide freely thereon. The downward movement of the loop 8 is limited by means of the stop 6, and the scale 7 indicates the movement of the handle 9 and 55 in consequence the depth of the cut of the saw blade hereinafter described.

Adjacent its upper end the standard 1 is provided with a slot 10 to form a guide for the inner end of the handle 9 in its vertical movement.

60

A supporting rod 11 is disposed parallel to and adjacent the standard 1 so as to slide through a guide 12 which is secured to the upper end of the standard 1. Midway its length the rod 11 is secured to the extreme inner end of the handle 9, as at 13, so that movement of the handle 9 is communicated to the supporting rod 11. The lower end of the supporting rod 11 works through a loop 14 formed on the inner end of the 70 bar 4, which loop and the guide member 12 form a guiding means for the supporting rod 11. The lower end of the supporting rod 11 is secured as at 15 to a casing 16, which casing is connected to or forms a part 75 of a motor 17, which motor has its upper end secured as at 18 to the upper end of the supporting rod 11. Vertical movement of the supporting rod 11 carries with it the motor and the casing, and all of their connected parts. A coiled spring 19 disposed around the supporting rod 11 normally maintains the parts in an elevated position so that the saw blade 20 does not extend 80 below the lowerline of the base formed by the feet 2.

85

A shaft 21 is carried in a bearing 22 and the saw blade 20 is secured thereon as by means of a nut 23. A beveled pinion 24 is secured on the shaft 21 and is arranged to 90 mesh with a gear 25 on the shaft 26 of the motor 17.

The device is operated by placing the base formed by the feet 2 upon the floor, ceiling, or partition 27, starting the motor 95 and pressing on the handle 9 to force the saw blade 20 therein.

Having thus fully described my invention, what is claimed as new and desired to secure by Letters Patent is:

100

1. A portable saw comprising a standard, a pair of feet pivoted thereto at the base thereof, said feet being adjustable on said pivot in a plane perpendicular to the plane of the said standard, a horizontally disposed transverse bar secured to said standard, and forming a guide to the one side thereof, a second guide secured to the top of said standard, a motor supporting member adapted to move in said guides, a motor secured to said supporting member, a saw mounted 105 in the latter, means for rotating said saw 110

from the said motor, a spring, for maintaining said motor and saw in normally raised position with respect to the said standard and means for bringing the said saw into contact with the work.

2. A portable saw comprising a standard, feet pivoted to said standard at the base thereof and arranged to operate in a plane perpendicular to the plane of the said stand-

ard, means for adjusting the position of the feet with respect to the standard, a plurality of guides secured to the said standard, a member adapted to move in said guides, a saw, a motor for driving the same, means for supporting said motor and saw on the said member, a spring on the latter for maintaining the motor and saw in inactive position and a handle secured to the said member for operating the saw.

3. A portable saw comprising a standard, a member secured thereto transversely thereof and forming a guide to the one side of the said standard, a second guide on the latter, a saw, a motor for driving the same,

means for movably supporting said motor 25 and saw in the said guides, a handle for operating said saw, a scale supported on the said member, an adjustable stop on said scale, and a measuring element secured to said handle and adapted to coöperate with 30 said scale and stop to measure the depth of the cut of the said saw.

4. A portable saw comprising a standard, a pair of pivoted feet on the same, arranged to be operable in a plane perpendicular to 35 the plane of the said standard, a motor and saw blade disposed above said feet and arranged to have movement with respect thereto, a spring for maintaining said motor and saw in normally raised inactive position, a handle disposed at an angle to the said standard for operating said saw and means for limiting and measuring the said movement of the saw.

In testimony whereof I have signed my 45 name to this specification.

FREDERICK MAURICE LASERSON.
